UNITED STATES PATENT OFFICE.

THEODORE C. MENGES, OF WATERLOO, IOWA, ASSIGNOR TO WILBUR W. MARSH, OF WATERLOO, IOWA.

SPEED-REGULATOR FOR INTERNAL-COMBUSTION ENGINES.

980,658.

Specification of Letters Patent.

Patented Jan. 3, 1911.

Application filed October 28, 1909. Serial No. 525,191.

To all whom it may concern:

Be it known that I, THEODORE C. MENGES, a citizen of the United States of America, and a resident of Waterloo, Blackhawk county, 5 Iowa, have invented certain new and useful Improvements in Speed-Regulators for Internal-Combustion Engines, of which the following is a specification.

My invention relates to speed regulators 10 for internal-combustion engines, and the object of my improvement is to conveniently and accessibly control the action of the valve-rod trip-lever by means of adjustable yieldable means mounted upon said lever and 15 coacting therewith. This object I have accomplished by the means which are herein-after fully described and claimed, and which are illustrated in the accompanying drawing, which is a representation of that part of 20 the speed-regulating mechanism of an internal-combustion engine which contains my said improvement.

The engine-bed or housing being designated by *a*, *w* is a slotted boss through whose 25 horizontal slot the valve-operating rod *b* plays to and fro. Upon the end of the rod *b* is an anti-friction idler *i* contacted by the edge of a cam-wheel *h* on the stud-shaft *g*, said cam-wheel being connected to a gear-wheel *k* on the same shaft to rotate therewith, and said gear-wheel being intermeshed with and driven by a pinion *l* on the power-shaft *j*. Upon said power-shaft is secured a fly-wheel *p*, and a sleeve *x*, annularly 30 grooved at *m* is slidably mounted on the same shaft. Governor-weights (not shown) are mounted in a well-known manner on the ends of the movable arms *u*, the latter having pivot-joints *o* with the fixed arms *t* projecting from said sleeve *x*. The governor 35 weights act to shift the sleeve *x* to and fro upon the shaft *j* in one direction or the other according to the variation of speed of rotation of the shaft. A bracket-arm *z* projects 40 from the body *a*, and its end is upturned to support the fulcrum-pivot *n* of a lever *q*. One end of said lever enters and engages the groove *m* in the governor-sleeve *x*, while the 45 other end of the lever extends forwardly, being bent at an angle toward the rod *b* to closely approach it. A detent *c* is projected 50 from the outer surface of the rod *b* in a proper location to engage a socket *d* in the inturned end of said lever when the speed 55 of the shaft *j* is such as to cause its governor

to so shift the sleeve *x* as to move the socketed part of said lever to its inner position. In this position of the lever-arm the detent *c* engages its socket, and the rod *b* is prevented from acting upon the valve and igniting- 60 mechanism of the engine until the decreased speed of the shaft *j* thereby occasioned causes the governor to shift the lever-arm out of the path of movement of said detent. When said detent is thus freed, the rod is actuated by means of the cam-wheel *h* as usual 65 and the engine has a constant succession of ignitions in its combustion-chamber. The forward arm of said lever is provided with an expansion *r* containing a bored out seat *s* 70 for a small coiled compression-spring *f* which bears against the outer end of the boss *w*. The outer part of the opening *s* is interiorly-threaded to receive an adjusting screw *e*, whereby the tension of said spring 75 may be adjusted at will. The spring operates to yieldingly oppose the too near approach of the socketed end of said lever to the rod *b*, except when under the action of the governor the lever-socket is thrust into 80 the path of movement of the detent *c*. The adjustment is thus convenient, since the adjusting-screw is very accessible, and direct in its action in company with the spring upon 85 the lever-arm.

Having described my invention, what I claim as new, and desire to secure by Letters Patent, is:

The combination with the frame, the detent-bearing valve-rod and the governor of 90 an internal-combustion engine, of a stop-carrying lever adapted to be oscillated by said governor to throw said stop into and out of the path of movement of said detent, said lever having a transverse interiorly-threaded opening in its end which carries 95 said stop, a coiled compression-spring in said opening and projecting therefrom and adapted to bear against said frame yieldingly to effect a resilient resistance to the outward throw of said governor, and an adjusting-screw in said opening adapted to adjustably bear against said spring to vary its 100 degree of tension.

Signed at Waterloo, Iowa, this 11th day 105 of Oct. 1909.

THEODORE C. MENGES.
